UNITED STATES PATENT OFFICE.

CHARLES R. HARRIS, OF WILLIAMSPORT, PENNSYLVANIA.

DESIGN FOR A SUSPENDER-BUCKLE.

SPECIFICATION forming part of Design No. 21,791, dated August 23, 1892.

Application filed July 2, 1892. Serial No. 438,826. Term of patent 14 years.

To all whom it may concern:

Be it known that I, CHARLES R. HARRIS, a citizen of the United States, residing at Williamsport, in the county of Lycoming and State of Pennsylvania, have invented and produced a new and original Design for Suspender-Buckles, of which the following is a specification, reference being had to the accompanying drawing, forming part thereof.

The accompanying drawing is a view in front elevation of my design.

The leading feature of my design is the raised circular seal or medallion formation shown, upon which is represented a bust of Columbus and the Goddess of Liberty hold-

ing a badge with the stars and stripes in one hand and a stainer in the other. Other details of the design may consist of the capitol, an anvil, and a cog-wheel.

What I claim is—

The design for suspender-buckles, herein shown and described.

In testimony whereof I have signed this specification in the presence of two subscribing witnesses.

CHARLES R. HARRIS.
